LOUD-SPEAKER

Leopold Iglück, Berlin, Germany, assignor to C.
Lorenz Aktiengesellschaft, Berlin-Tempelhof,
Germany, a company

Application September 6, 1940, Serial No. 355,621
In Germany November 3, 1939

2 Claims. (Cl. 181—31)

Loudspeakers installed on shipboard or in tank-stations, damp rooms or the like, being fixed there to the ceiling, for instance, require their operative system to be protected from water and moisture. For this purpose the system is enclosed in a water-tight metal casing. The protection afforded in this way, however, is not sufficient since there is no provision for closing the sound hole of the casing.

The present invention provides for closing the sound hole by means of the sound distributing body located in front thereof. The invention thus serves to increase the life of loudspeakers arranged in the open air or in damp rooms.

The drawing shows one embodiment of the invention. Fig. 1 is a sectional view, taken along line 4—4 of Fig. 2, and Fig. 2 a plan view of this embodiment.

The casing 1 for the loudspeaker LS is made of sound-proof material and has a flange 2 pierced with holes for fixing the loudspeaker to the ceiling C of the respective room. The sound hole 11 of the casing can be closed by the sound distributing body or cone 3, as indicated in dotted lines.

In the case here illustrated by way of example a cylindrical bar 4 is attached to body 3 and has a handwheel or other suitable handle 5 rigidly fixed to it. Bar 4 is formed with a screw 6

adapted to engage with a thread 7 provided in a sleeve 8. This sleeve is fixed to props 9 of the casing 1 and serves as a guide for bar 4 and body 3.

5 In order to close the opening 11 by means of the body 3 the assembly 5, 6, 4, 3 is raised until the thread 6 comes against thread 7. Thread 6 is then screwed into the thread 7 with the aid of wheel 5, whereby the edge of body 3 is pressed against the edge of the hole 11. Body 3 may be provided to such end with an annular rubber joint 10.

What is claimed is:

1. A waterproof housing for a loud speaker comprising, in combination, a waterproof casing enclosing said loud speaker, said casing having a sound opening therein, and a sound distributing body movably mounted in front of said sound opening and being movable into position against said casing to seal said sound opening against entry of moisture into said casing.

2. In a combination according to claim 1, a guide for the sound distributing body, a threaded member forming part of this guide, a handle carried by the sound distributing body, and a threaded member fitted to such handle and adapted to engage with the threaded member of said guide.

LEOPOLD IGLÜCK.
